[57] CLAIM

The ornamental design for a combined clock and pen
case, as shown and described.

DESCRIPTION

FIG. 1 is a perspective view of a combined clock and
pen case showing my design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof, the left
side being a mirror image of that shown.

FIG. 1

FIG. 2

FIG. 3

FIG. 4

FIG. 5

FIG. 6
